MODULATING AND ON-OFF FUEL CONTROL APPARATUS

Charles E. Hajny, Milwaukee, Wis., assignor to Baso Inc., Milwaukee, Wis., a corporation of Wisconsin

Application September 15, 1958, Serial No. 761,666

46 Claims. (Cl. 236—1)

This invention relates to improvements in modulating fuel control apparatus, and this application is a continuation-in-part of my application Serial Number 665,367 filed June 6, 1957 and now abandoned, which was a continuation of my application Serial Number 378,519, filed September 4, 1953 and now abandoned, and of my application Serial Number 479,906 filed January 5, 1955 and now abandoned.

In the development of modulating apparatus for controlling the flow of fuel to fluid fuel burning equipment, the operating characteristics of the fuel burner are an important consideration. For every burner there is a safe minimum amount of fuel which is required for the maintenance of a stable flame. On the other hand, fuel in amount substantially greater than the aforementioned safe minimum must be supplied to the burner for safe ignition thereof.

It is a general object of the present invention to provide an improved modulating fuel control apparatus having a modulator valve actuated by a modulating condition responsive, for example temperature responsive, actuating mechanism to provide modulation of the fuel flow to a main burner, said apparatus permitting the burner to be safely ignited at any time, regardless of what the response of said actuating mechanism to the ambient temperature may be at the time.

More specifically, it is an object of the invention to provide an improved apparatus of the character described which does not require that the room temperature cool to the lower end of the modulating range before the modulator valve can be opened sufficiently to permit safe ignition.

Another object of the invention is to provide an improved apparatus of the aforementioned character wherein during an ignition operation the burner may be ignited with a full burner capacity flame and holds said flame for a predetermined controlled interval, after which the burner is returned to the control of the modulating mechanism.

Another object of the invention is to provide an improved modulating fuel control apparatus of the class described including an on-off valve as well as a modulator valve, there being means for positioning the modulator valve in ignition position at any time that the on-off valve is opened.

Another object of the invention is to provide an improved modulating fuel control apparatus of the character described, wherein the modulator valve can throttle the fuel down to a minimum amount consistent with maintenance of a safe flame, and the on-off valve provides for complete shut-off of the fuel.

Another object of the invention is to provide an improved modulating fuel control apparatus of the aforementioned character wherein the modulator valve is modulated by the actuating mechanism between a minimum safe flow-permitting position and a full burner capacity ignition position in response to the changes in the ambient temperature, there being auxiliary actuating means

operable to overcall said actuating mechanism and to position the modulator valve in said ignition position when the on-off valve is opened, irrespective of the response of the actuating mechanism to the ambient temperature at the time.

5 A further object of the invention is to provide an improved modulating control apparatus of the character described wherein the modulator valve is biased toward the minimum flow-permitting position, and the overcalling auxiliary actuating means actuates said valve to said ignition position against said bias when the on-off valve is closed, said auxiliary actuating means releasing said modulator valve to the control of said actuating mechanism upon opening of said on-off valve, and there being time delay means for retarding the return of the modulator valve to the control of said actuating mechanism after the on-off valve is opened, said time delay being sufficient to insure safe ignition of the burner.

20 A more specific object of the invention is to provide an improved modulating control apparatus wherein the auxiliary actuating means takes the form of a diaphragm connected to the modulator valve and exposed on one side to the fluid pressure of the fuel on the upstream side of the on-off valve and exposed on its other side to 25 the fluid pressure on the downstream side of said on-off valve, whereby closure of said on-off valve causes movement of the diaphragm and modulator valve in a valve opening direction against the bias of said valve, and opening of said on-off valve equalizes the fluid pressure on the opposite sides of the diaphragm to permit movement of the modulator valve and diaphragm in a valve closing direction under said bias.

Another specific object of the invention is to provide an improved apparatus of the character described wherein 30 the time delay means comprises a uni-directional dashpot mechanism connected to the modulator valve and operable to retard the movement of the latter in a valve closing direction.

Another object of the invention is to provide an improved apparatus of the character described wherein the on-off valve is provided with an electro-responsive operator powered from a source of electric energy and under the control of a condition responsive device, for example a thermostat, independent of the modulating mechanism.

45 Another object of the invention is to provide an improved fuel control apparatus of the aforementioned character wherein the modulating mechanism modulates the modulating valve member between the minimum flow position and the ignition position in response to normal fluctuations in temperature, and the thermostat cycles the on-off valve in response to predetermined high temperatures.

Another object of the invention is to provide an improved modulating control apparatus that is relatively simple in construction, positive and safe in operation, and otherwise well adapted for the purposes described.

Other objects and advantages of the invention will appear as the description proceeds, reference being had to the drawings accompanying and forming a part of this specification. In the drawings, which illustrate one complete embodiment of the invention, and wherein like characters of reference indicate the same parts in all of the views:

65 Figure 1 is a fragmentary longitudinal vertical sectional view of one form of the improved modulating fuel control device, the associated fuel burning apparatus and the electrical control circuit therefor being shown semi-diagrammatically;

70 Figure 2 is a plan view of the improved modulating fuel control device, the modulating actuating mechanism,

as well as the on-off valve and its operator being removed, and parts being broken away and shown in section;

Figure 3 is an enlarged transverse vertical sectional view taken approximately along the line 3—3 of Figure 1;

Figure 4 is a fragmentary semi-diagrammatic view of another form of the invention; and

Figure 5 is a view similar to Figure 1 showing a form of the invention having two electroresponsive valve operators.

Referring now to Figure 1 of the drawing the invention comprises an improved modulating fuel control device indicated generally by the numeral 5, said device being interposed in the fuel supply line to a fluid fuel burner 6 to control the flow of fluid fuel thereto. The device 5 comprises an on-off valve 7 and a modulating valve 8 serially arranged in the fuel stream, there being an operator 9 for the on-off valve 7, and a condition responsive, for example temperature responsive, actuating mechanism 10 for the modulating valve 8. The device 5 also includes an auxiliary actuating mechanism 11 for the valve 8 as well as a uni-directional time delay or movement retarding mechanism 12 for the valve 8. (See Figures 2 and 3.)

More specifically, the device 5 has a body or casing 13 provided with an inlet chamber 14, an outlet chamber 15 and an intermediate chamber 16. A bore 17 affords communication between the chambers 14 and 16, and a tubular insert 18 in said bore provides an annular valve seat 19 in the chamber 14. A valve member 20 coacts with the seat 19 said valve member and seat comprising the modulating valve 8 which controls the flow of fluid fuel into the chamber 16 in a manner to be hereinafter more fully described. A bore 21 affords communication between the chambers 15 and 16, and an annular valve seat 22 surrounds the margin of the bore 21 within the chamber 16. A valve member 23 coacts with the seat 22, said valve member and seat comprising the on-off valve 7 which controls the flow of fluid fuel from the chamber 16 into the chamber 15 as will hereinafter appear.

The casing 5 is provided with an external recess 24 below the chamber 14, and a bore 25 extends through the wall portion separating said chamber and recess, said bore being coaxial with the bore 17. The valve member 20 is fixed to a stem 26 which projects through the bores 25 and 17, there being a coiled compression spring 27 in the chamber 14 surrounding said stem and biasing the valve member 20 toward the seat 19. The tubular valve insert 18 may be provided with a coaxial annular guide 28 through which the stem 26 slidably extends, said guide being supported by spaced radial legs 29. The upper end of the stem 26 is pivotally connected, as by a pin 32, to one end of an arm 30. The other end of the arm 30 is fixed to a pivot shaft 31 so that during axial movement of the stem 26, the arm 30 swings on the axis of the shaft 31.

The modulating mechanism 10 for actuating the modulator valve 8 comprises a rectangular casing 33 mounted on the body 13 and having a bottom plate 34 providing a cover for the body 5 and sealing off the chamber 16 therebelow. The casing 33 also has end walls 35 and 36, side walls 37 and 38 and a cover 39. Referring to Figure 3, the casing end wall 36 is formed with a circular aperture 40 to receive the externally threaded open end portion 43 of a tubular fitting 41. The fitting 41 has a centrally apertured end wall 42 opposite its externally threaded end, and has an external annular shoulder 44 in abutment with the end wall 36 at the margins of the aperture 40. An annular spacer 45 surrounds the threaded portion 43 of the fitting 41 and abuts the outer surface of the end wall 36, said spacer having a peripheral slot 46 as shown. The fitting 41 is held in position by a nut 47 which is threaded on the portion 43 and engages the spacer 45 as shown. The threaded end

portion 43 is provided with a longitudinal slot 48 as shown, the slot 46 being in registry with the slot 48.

Positioned within the fitting 41 is a condition responsive, for example temperature responsive, expansible and contractible bellows assembly 49. The assembly 49 includes an expansible and contractible bellows 51 provided with an end fitting 50 having a hermetically sealed connection therewith. The end fitting 50 has a tubular extension or guide sleeve 52 projecting axially within the bellows 51 and having a cross-bore 53. The bellows 51 is also provided with an opposite end fitting 54 which has a hermetically sealed connection therewith. The end fitting 54 has a stem portion 55 projecting axially within the bellows 51 and telescopically slidable within the guide sleeve 52 of the end fitting 50. The end fitting 54 is also provided with an external stem portion 56 which slidably projects through the aperture in the end wall 42 of the fitting 41. A coiled compression spring 57 surrounds the stem 56 within the fitting 41, and biases the bellows end fitting 54 toward the opposite end fitting 50.

Means are provided for adjusting the position of the bellows assembly 49 within the fitting 41 to thereby provide a range adjustment. A manually engageable knob or dial 59 is internally threaded for engagement with the threaded portion 43 of the fitting 41. A set screw 58 is coaxially threaded through the knob 59 and engages the bellows end fitting 50 as shown. The screw 58 is locked in place relative to said knob by a lock nut 60. The knob 59 has a peripheral projection which may take the form of a screw 61 threaded radially thereinto and positioned for engagement with a tongue 62 projecting from the end wall 36 to limit the rotation of the knob 59 and hence the amount of manual adjustment of the bellows position. The screw 61 may also serve as a range indicator. The setting of the adjustment screw 58 relative to the knob 59 is preferably made at the factory.

The bellows end fitting 50 is provided with a passage 63 which communicates with the bore of the guide sleeve 52 thereof, and a tube 64 affords communication between the passage 63 and a temperature sensing bulb 65. The tube 64 has its inner end sealingly positioned in the passage 63 and extends radially outwardly through the slots 48 and 46 as shown. The bulb 65 is preferably located at the comfort level in the space being heated by the burner 6, for example at the normal location for a room thermostat. With suitable adjustment, however, the bulb 65 may be mounted in other locations, for example in the cold air return of the heating unit.

The bellows 51, tube 64 and bulb 65 are filled with a liquid having a high coefficient of expansion and having a boiling point at working pressures which is above the highest ambient temperature to which it might be subjected. The fill exists substantially entirely in the liquid phase and is commonly known as a "solid liquid" type fill, as differentiated from fills which exist in the vapor phase as well as the liquid phase. With a "solid liquid" type fill the actuating forces are created by thermal expansion of the liquid fill only, rather than by vapor pressure. Chloroform is illustrative of a type of liquid well adapted for use as a fill for the bellows 51.

Expansion and contraction of the bellows 51 in response to changes in temperature sensed by the bulb 65 causes actuation of the valve stem 26 and valve member 20, the actuating forces being transmitted to said stem through a uni-directional force transmitting connection which will now be described. A bearing sleeve 66 is threaded through a suitable aperture in the bottom plate 34 of the casing 33 and is coaxial with the stem 26. A stem 67 is axially slidable positioned in the bearing sleeve 66 and is formed with an external annular groove 68 for receiving a sealing ring 69 which provides a gas-tight seal between the stem 67 and the bearing sleeve 66. The lower end of the stem 67 is rounded and engages the top side of the arm 30 coaxial with the

stem 26, as shown in Figures 1 and 3. The upper end of the stem 67 is also rounded, and fixed to said stem adjacent its upper end is a spring retaining disc 70. A coiled compression spring 71 surrounds the stem 67 and bearing sleeve 66, having one end in abutment with the retaining disc 70, and having its opposite end resting on the bottom plate 34.

A bell crank lever 72, which may be channel-shaped in transverse cross-section, is pivotally mounted on a pin 73 carried by the side walls 37 and 38. The side flanges of one arm 110 of the lever 72 are notched as at 74. The adjacent end of the stem 56 is flattened, as at 75, and passes through a suitable aperture in the web portion of the lever 72 adjacent the notches 74, and a pin 76 extends through the flattened portion of the stem 56 and is positioned in the notches 74 as shown. The other arm 111 of the lever 72 rests on the upper end of the stem 67, and the bias of the spring 71 urges the lever 72 in a clockwise direction (as viewed in Figure 3) to thereby seat the pin 76 in the base of the notches 74. A set screw 77 having a lock nut 78 may be threaded through the casing end wall 35 and may be adjusted to limit the clockwise movement of the lever 72.

It is apparent that upon contraction of the fill in the bellows 51 the bias of the spring 57 causes a counter-clockwise force to be exerted on the lever 72 and a downward force to be exerted on the stems 67 and 26 as well as on the valve member 20, said movement being against the bias of the springs 71 and 27. It is also apparent, however, that during expansion of the fill in the bellows 51 no substantial moving force is exerted by the stem 56 on the lever 72, but the valve member 20 and stems 26 and 67 are moved upwardly and lever 72 is rotated in a clockwise direction by the bias of the springs 71 and 72.

In the illustrated embodiment of the invention the adjustment screw 77 may be so positioned that the valve member 20 cannot fully close, the minimum open position of said valve member permitting sufficient fuel flow to maintain a stable flame at the burner 6 when the on-off valve 7 is open. It is preferable, however, to permit the valve member 20 to close completely, and to utilize a by-pass afforded by the passage 86 which communicates between the chambers 14 and 16 as shown in Figure 3. An adjustment screw 87 intersects the passage 86 to provide control of the amount of fuel flow through said passage, the amount of fuel permitted to flow through said passage being sufficient to maintain a stable flame at the burner 6 as aforementioned.

Means are provided for disposing the valve member 20 in a full open or ignition position whenever the on-off valve 7 is opened, said means including a diaphragm 79 forming a chamber 80 with the recess 24 of the body 13 and held in place by a coverplate 81 which sealingly clamps the periphery of the diaphragm 79 to form a chamber 82 therewith. The diaphragm 79 is provided with a backing plate 83 which is suitably fixed to the lower end of the stem 26 as shown. A passage 84 (Figure 1) affords communication between the chambers 16 and 80, and an angular passage 85 affords communication between the chambers 15 and 82.

It will be noted that when the valve member 23 of the on-off valve 7 closes, the fluid pressure in the chambers 15 and 82 drops to atmospheric, whereas the pressure in the chambers 16 and 80 builds up to actuate the diaphragm 79 and its plate 83, stem 26 and valve member 20 downwardly, to move the valve member 20 to its ignition position against the bias of the spring 27. This actuation of the valve member 20 is independent of the position of the stem 26, and if the valve member 23 is opened when the remaining parts of the device are in the position shown, the arm 30 connected to the stem 26 is swung downwardly away from the stem 67 as the stem 26 and valve member 20 are moved downwardly with the diaphragm 79 and its plate 83. When

the valve member 23 is opened, the pressures on the opposite sides of the diaphragm 79 become equalized and the stem 26 and valve member 20 are urged in a valve-closing direction under the bias of the spring 27 until the arm 30 reengages the stem 67 to thereby place the valve member 20 again under the control of the modulating mechanism 10.

Means are provided for retarding the aforementioned return movement of the valve member 20 so that fuel is permitted to flow through the valve 8 in substantial quantity and for a substantial period of time after opening of the valve 7, in order to permit proper ignition of the fuel at the burner 6 with a full burner capacity flame. In the illustrated embodiment of the invention this time delay means takes the form of the uni-directional dashpot mechanism 12 shown most clearly in Figures 2 and 3. The body 13 is formed with a rectangular recess 88 separate from the chamber 16 and closed by the bottom plate 34 of the casing 33. Referring to

Figure 2, the pivot shaft 31 extends rotatably through a transverse bore 89 which communicates between the chamber 16 and recess 88, and said shaft is formed with an external annular groove for receiving a sealing ring 90.

Within the recess 88 one end of an arm 91 is fixed to the pin 31. Adjacent the opposite end of the arm 91 the casing 13 is formed with a vertical bore 92 which opens into the bottom of the recess 88. A stem 93 is fixed at its upper end to the arm 91, as by a transverse pin 94, and depends into the bore 92 as shown. A tubular piston 95 has a loose fit within the bore 92 and is connected to the lower end of the stem 93 as by a pin 96. The piston 95 has a lower end wall provided with an aperture 97, there being a ball type check valve 98 adapted to seat in said aperture. The piston 95 is also formed with a cross-bore 99, and a pin 100 limits the movement of the ball 98 within the piston 95. The recess 88 and the bore 92, as well as the interior of the piston 95, are filled with a fluid, for example mineral oil, to provide the necessary fluid friction for dashpot action.

It is apparent that as the arm 30 is swung downwardly during opening of the valve member 20, the arm 91 is simultaneously swung downwardly to move the piston 95 downwardly within the bore 92. The piston 95 can move freely in a downward direction within the bore 92 since the fluid in said bore displaced by said piston movement can flow upwardly through the aperture 97 and cross-bore 99 as well as through the radial clearance around the outside of said piston. However, when the on-off valve 7 is opened and the valve member 20 begins to move upwardly under the bias of the spring 27, this upward movement is retarded by the fluid friction in the dashpot mechanism 12, since the piston 95 cannot move freely in an upward direction. The aforementioned retardation occurs because the ball valve 98, upon upward movement of the piston, seats on and closes the aperture 97, thereby limiting the flow of the dashpot fluid displaced by piston movement to the path around the piston 95 only. As a result, a time delay is provided which holds the valve member 20 open for a predetermined period after the on-off valve 7 is opened.

The on-off valve 7 may be operated in any suitable manner. In the illustrated embodiment of the invention the valve 7 is provided with a solenoid operator 9 having a threaded mounting in a suitable internally threaded bore 101 in the casing 13. The operator 9 has a reciprocating stem 102 which is suitably connected to the valve member 23 as by a pin 103. The operator 9 is connected in circuit with a suitable source of electrical energy as by conductors 104 and 105. A circuit controlling device 106, which may be condition responsive, as for example a room thermostat, is interposed in the operator circuit for cycling the operator 9, and hence the valve 7, in response to predetermined changes in the temperature sensed by said thermostat. The thermostat 106 may also be located at the comfort level in the space being

heated, i.e. in the normal location for a room thermostat, and with respect to the modulating means aforescribed it preferably functions as a high limit device.

The operation of the improved fuel control apparatus will now be described. Assuming an original condition wherein the room to be heated by heat from the burner 6 is cold, the thermostat 106 calls for heat, and the operator 9 is energized, and hence holds the valve 7 open. At the same time the modulator bellows 51 is in its most contracted condition, and the bellows fittings 54 is in abutment with the end of the guide sleeve 52 of the bellows end fitting 50. The spring 57, acting against the bellows end fitting 54 and through the stem 56, lever 72, and stems 67 and 26, holds the modulating valve member 20 in its lowermost or wide open position, permitting maximum gas flow to the burner 6, whereupon said burner is ignited by the pilot burner 107. As the room, and therefore the control bulb 65, heats up, the bellows 51 gradually expands and throttles the gas flow through the valve 8 until the valve member 20 eventually seats on the valve seat 19. At this time the only gas flow to the burner 6 is that which can flow through the bypass 86 and through the clearance around the stem 26 in bore 25, and as previously mentioned, said flow is the minimum sufficient to maintain a safe flame at the burner 6. On warm days when the minimum safe flame supplies more heat to the room than is lost from the room, the thermostat 106, acting at a high limit, snaps off the operator 9 to close the valve 7.

When the valve 7 closes, the fluid pressure of the fuel immediately builds up in the chamber 80 and drops to atmospheric in the chamber 82. This pulls the modulating valve member 20 down to wide open ignition position almost instantly, as the dashpot piston 95 simultaneously moves downwardly in the bore 92. As the room gradually cools, the thermostat 106 calls for heat and causes the operator 9 to open the valve 7, whereupon the fluid pressure in the chambers 80 and 82 becomes equalized. The time delay mechanism then operates to retard the closing movement of the valve member 20 until the burner 6 has been safely ignited at full gas pressure by the pilot burner 107. The stem 26, valve member 20 and arm 30 are moved slowly upwardly until the arm 30 reengages the stem 67 to again place the valve member 20 under the control of the modulating mechanism 10.

It is apparent that the improved fuel control apparatus permits the burner 6 to be ignited with a safe full burner capacity flame and to hold this flame for a predetermined period of controlled duration irrespective of the response of the modulating mechanism 10 to the temperature sensed by the bulb 65, and also irrespective of the setting of the adjustment knob 59 of said modulating mechanism.

Figure 4 shows another form of the invention in which the modulating bellows mechanism 49 controls the operation of both the modulating valve 8 and the on-off valve 7. In this form of the invention the thermostat 106 shown in Figure 1 can be omitted. In Figure 4 the parts indicated by primed numerals correspond to parts indicated in Figure 1 by the same numerals unprimed. A circuit controlling device 106', which may take the form of a normally closed switch, is interposed in the conductor 105' connecting one side of the solenoid coil 9' to the source. The switch 106' is mounted within the casting 33' and has a spring-loaded stem or push button 112 positioned for engagement by an end portion 113 of the bell crank lever 72'.

During normal fluctuations in the temperature, the portion 113 of the arm 72' does not engage the stem 112 of the switch 106', and therefore, said switch permits current flow from the source to the solenoid coil 9', which, in turn, holds the on-off valve 7' in open position. When the temperature of the room reaches a predetermined high limit, however, the portion 113 of the arm 72' engages and depresses the button 112 to open the switch 106' and deenergize the solenoid coil 9', where-

upon the on-off valve 7' closes. Cooling of the room below the high limit temperature moves the portion 113 of lever 72' out of engagement with the button 112, thereby permitting closure of switch 106' and reenergization of the solenoid 9', whereupon the latter opens the on-off valve 7'.

Referring to the form of the invention shown in Figure 5 of the drawing, the improved modulating fuel control apparatus there illustrated comprises a fuel control device indicated generally by the numeral 5' and having a valve body 13' provided with an inlet chamber 14', an outlet chamber 15' and an intermediate chamber 16'. The control device 5' is interposed in the fuel supply line to a fluid fuel burner 6' and controls the flow of gaseous fuel to said burner by means of an on-off valve 7' and a high-low modulating valve 8' serially arranged in the fuel stream, there being an electroresponsive operator 9' for the on-off valve 7', and an electroresponsive operator 10' for the high-low valve 8'. Condition responsive, for example temperature responsive, circuit-controlling means is provided to control the energization of the operators 9' and 10', and hence the operation of the valves 7' and 8'. Fluid pressure responsive auxiliary actuating mechanism 12' including time delay or movement retarding means coacts with the valve 8' to afford safe ignition, in a manner which will hereinafter more fully appear. A bore 17' affords communication between the chambers 14' and 16', there being an annular valve seat 18' surrounding said bore in the chamber 14' and with which the high-low valve 8' is cooperable. A bore 19' affords communication between the chambers 16' and 15', there being an annular valve seat 20' surrounding said bore within the chamber 16' and with which the on-off valve 7' coacts.

The auxiliary actuating mechanism 12' affords a closure for a bottom opening 21' in the chamber 16' of the valve body 13'. The mechanism 12' may, if desired, be made up as a subassembly for attachment to the body 13', said mechanism comprising a plate 23' having a peripheral rim of increased thickness, and a dished cover plate 24' between which and said plate a flexible diaphragm 25' is marginally clamped as shown. The aforementioned subassembly may be held together by a drawn ring 26' having a radially inwardly directed annular flange 27' for marginally clamping a flexible diaphragm 28' between itself and the rim of the plate 23' as shown, said ring 26' also having a radially inwardly rolled annular edge clampingly engaging the periphery of the cover plate 24' as shown. The mechanism 12' may be attached to the body 13' by means of screws 30' as shown. The cover plate 24' and the diaphragm 25' afford a chamber 31' in which a helical compression spring 32' is disposed, one end of said spring engaging the cover 24', and the other end engaging a back-up plate 33' fixed to the underside of the diaphragm 25', as by a rivet 34'. A passage 35' extending through a wall portion of the valve body 13', the flange 27', the clamped margin of the diaphragm 28', the rim of the plate 23', the clamped margin of the diaphragm 25' and an inner marginal portion of the cover 24' affords communication between the outlet chamber 15' of the body 13' and the chamber 31'.

The plate 23' is formed with a relatively large aperture 36' and with a restricted aperture 37' as shown. Surrounding the margin of the aperture 36' on the underside of the plate 23', said plate is provided with an annular valve seat with which a reed type check valve 38' coacts. The plate 23' and the diaphragm 28' form a chamber 39', and said plate and the diaphragm 25' form a chamber 40', both of said chambers being filled with a suitable hydraulic fluid. A back-up plate 41' and a generally U-shaped connecting member 42' are fixed to the upper side of the diaphragm 28', as by nut and bolt members 43' and 44', respectively.

A force transmitting connection is provided between the valve member 8' and the auxiliary actuating mech-

anism 12' to overcall the control means comprising operator 10' and valve member 8' and provide for the disposition of the valve member 8' in an open position upon closing of valve member 7', thereby permitting sufficient fuel flow for safe ignition whenever the on-off valve member 7' is moved from closed to open position at a later time. Thus, the auxiliary actuating mechanism 12' overcalls or overrides the disposition of the valve 8' by the operator 10'. In the illustrated embodiment of the invention, the aforementioned connection comprises a lever 45' pivotally mounted within the chamber 16' on a suitable bearing 46' and having one end thereof positioned for abutment with a stem 47' depending from the valve member 8' as shown. The opposite end of the lever 45' is suitably connected, as by a link 48', with the connection member 42'.

In order to provide at least the minimum amount of fuel flow necessary for the maintenance of a stable flame whenever the on-off valve member 7' is open, the valve body 13' is provided with a by-pass 49' affording communication between the chambers 14' and 16' as shown. An adjustment screw 50' is provided for the adjustment of the amount of fuel which can flow through the passage 49'.

In the illustrated embodiment of the invention the electrical energy for powering the electroresponsive actuators 9' and 10' is derived from a line comprising conductors 51' and 52'. It is understood, of course, that the current supplied to the actuators 9' and 10' may be of any suitable or desired magnitude, including that provided by a thermoelectric generator. One terminal of the electroresponsive actuator 10' is connected in circuit with the line wire 51' by a conductor 53', the latter having interposed therein a tapped electrical resistance element 55'. The other terminal of the actuator 10' is connected in circuit with the line wire 52' through a conductor 54' and a condition responsive circuit-controlling device 56' comprising a stationary contact 57' and a snap leaf contact 58'. One terminal of the actuator 9' is connected in circuit with the tap of the resistance element 55' by a conductor 59', and the other terminal of said actuator is connected in circuit with the line wire 52' by a conductor 60' having interposed therein a condition responsive circuit-controlling device 61' comprising a stationary contact 62' and a coacting snap leaf contact 63'. The snap leaf contacts 58' and 63' have actuating tongues 64' and 65' respectively which when depressed, i.e. moved toward the right in the drawing, effect snapping of the snap leaves into engagement with the coacting fixed contacts, and when released permit the snap leaves to snap out of engagement with said fixed contacts.

While the response of the circuit-controlling devices 56' and 61' may each be under the control of a separate condition responsive actuating means, it is preferred to utilize a single actuating means for both of said devices. The actuating means may take a number of different forms, and in the illustrated embodiment, takes the form of a vapor-filled bellows 66' having an adjustably fixed end wall 67' engaged by an adjustment screw 68' threaded through a fixed support member 69'. The opposite end wall 70' of the bellows 66' is movable and has fixed thereto an axially projecting stem 71' having shoulder means 72' for coaction with the snap leaf tongue 64' and shoulder means 73' for coaction with the snap leaf tongue 65'. The stem 71' carries at its outer end an abutment member 74' which engages one end of a helical compression spring 75'. An abutment member 76' engages the opposite end of said spring and is provided with a stem 77' axially slidably in a fixed bearing 78' and having its outer end engageable by a rotary cam 79' carried by a shaft 80'. Suitable means (not shown) is provided for manually adjusting the position of rotation of the cam member 79' and thereby adjusting the compressive force exerted on the bel-

lows 66' by the spring 75'. Adjustment of the compressive force exerted on the bellows 66' affords an adjustment of the control points of the circuit-controlling devices 56' and 61'. As shown in the drawing, the electrical resistance 55' is disposed adjacent the bellows 66' to afford anticipation in a manner to be hereinafter set forth. The condition responsive circuit-controlling means 11' illustrated in the drawing comprises what is commonly known as a two-stage thermostat.

In describing the operation of the improved control apparatus it will be assumed that the temperature of the room or space being heated, as sensed by the bellows 66', is such that the thermostat blade 63' engages the fixed contact 62' but the blade 58' is disengaged from the contact 57'. This disposition of the contacts results in the actuator 9' being energized to hold the on-off valve 7' open as shown, and in the actuator 10' being deenergized to permit closure of the valve member 8', for example by gravity. Whenever the actuator 9' is energized, the portion of the resistance element 55' between the conductors 53' and 59' is also energized to cause generation of a small output of heat providing a low level of heat anticipation. Where no such low level anticipation is desired, however, the conductor 59' may be connected directly to the conductor 53' or line wire 51', so that no portion of the element 55' is energized during low fuel flow. With the valve member 8' closed, the only gas which can flow to the burner 6' is that which can flow through the by-pass 49' to provide a low flame condition at the burner 6'.

In the event that the heat supplied by the burner 6' with a low flame is greater than the heat loss from the space being heated, thereby causing the temperature of the space to increase and exceed a predetermined high limit temperature, the bellows 66' expands and the shoulder means 73' moves the snap leaf tongue 65' to the right to thereby effect snapping of the blade 63' out of engagement with the fixed contact 62'. This, of course, effects deenergization of the operator 9' and the valve member 7' is permitted to close, for example by gravity and fuel pressure, thereby shutting off all fuel flow to the burner 6'.

Immediately upon closure of the valve member 7' the fuel pressure builds up in the chamber 16', thereby forcing the diaphragm 28' and back-up plate 41' downwardly to force the hydraulic fluid out of the chamber 39' and into the chamber 40' through the aperture 36' and past check valve 38' and through the aperture 37'. Downward movement of the back-up plate 41' pulls the link 48' and the connected end of the lever 45' downwardly to pivot said lever in a clockwise direction and thereby lift the stem 47' and valve member 8'. The valve member 8' is lifted to an open position which may be its full open position, or may be a position of lesser opening affording sufficient fuel flow for safe ignition of the burner 6' when the on-off valve 7' is subsequently opened. The auxiliary actuating mechanism 12' holds the valve member 8' in this raised position as long as the fuel pressure in the chamber 16' is maintained at full line pressure by closure of the on-off valve member 7'.

When the hydraulic fluid is forced from the chamber 39' into the chamber 40', said fluid forces the diaphragm 25' and plate 33' downwardly against the bias of the spring 32'. The fluid displaced from the chamber 31' by this diaphragm movement is vented into the outlet chamber 15' through the passage 35'.

As the room or space cools after extinguishment of the burner flame, the bellows 66' contracts and moves the stem 71' and shoulder means 72' and 73' toward the left. At a predetermined temperature the snap leaf 63' snaps into engagement with the fixed contact 62', thereby energizing the actuator 9' and effecting opening of the on-off valve 7'. Since the high-low valve 8' is already opened, sufficient fuel flow is available to the

burner for ignition thereof by suitable ignition means, for example by a constantly burning pilot burner 81'. When the on-off valve member 7' is moved from closed to open position the fuel pressure within the chamber 16' drops, and the pressure within the chamber 15' rises until the pressures within said chambers are substantially equalized. The auxiliary actuating mechanism 12' does not, however, permit the high-low valve member 8' to immediately move to closed position, said valve member being held in an open position for a sufficient length of time to permit ignition of the burner 6'. This operation occurs by virtue of the reed check valve 38' which prevents return fluid flow through the aperture 36' when the pressures within chambers 15' and 16' approach equality. As a result, when the compression springs 32' forces the displaced hydraulic fluid from the chamber 40' back into the chamber 39', said fluid can flow through the restricted aperture 37' only, and a substantial period of time elapses before the diaphragm 28' and the plate 41' return to their normal positions shown in the drawing and permit the high-low valve member 8' to return to its seat 18'. When the valve member 8' is seated, the fuel flow to the burner 6' is again limited to that which can flow through the bypass 49'.

If a low flame at the burner 6' affords insufficient heat to maintain the proper room temperature, the bellows 66' continues to contract, and a predetermined temperature the shoulder means 72' permits the snap leaf 58' to snap into engagement with the fixed contact 57'. This causes energization of the actuator 10' and of entire length of the resistance element 55'. The high-low valve member 8' is immediately opened by the energized actuator 10', and full capacity fuel flow to the burner 6' results. As the temperature of the room rises with the high burner flame, the bellows 66' expands, and a higher level of anticipation is provided by the relatively large amount of heat supplied from the full length of the anticipator 55'. The bellows 66' expands and contracts thereafter, cycling the snap leaf 58' and thereby the high-low valve member 8' in accordance with normal fluctuations in temperature, i.e. temperatures below the predetermined high limit temperature at which the snap leaf 63' is snapped out of engagement with the fixed contact 62' to close the on-off valve 7'. However, at any time that the room temperature does reach the aforementioned high limit temperature, corresponding expansion of the bellows 66' effects disengagement of the snap leaf 63' from the contact 62', deenergizing the actuator 9', closure of the valve member 7', and shut-off of all fuel flow to the burner 6'.

In the operation of the improved fuel control apparatus just described, the application of a separate automatically applied level of anticipation for each of the levels of fuel flow avoids overshooting and short cycling of the heating system. Selection of the proper resistance element 55' affords accurate control of the anticipation provided at both levels of fuel flow.

By virtue of the fact that the improved fuel control apparatus of Figure 5 provides either high fuel flow, low fuel flow, or no fuel flow, quick warm-up of the heated space, for example, after night turn-down, is provided, since the burner operates at full fuel capacity until the room temperature reaches a level calling for low fuel flow. The improved control apparatus of Figure 5 does not derate the heater, and safe ignition is insured without requiring the temperature of the heated space to cool through the entire modulating range after shut-off of the burner. Of substantial commercial importance is the fact that the improved control apparatus of Figure 5 is universally adaptable for use on any selected size heater up to the maximum size for which the control is rated. Its adaptability is further enhanced by the fact that it performs with equally high efficiency regardless of the type of gas burned in the selected heater, no change or

adjustment other than adjustment of the setting of the minimum flow adjustment screw 50' being required for adaptation of the control to a particular fuel.

The illustrated forms of the invention have been selected for the purpose of disclosure only and are not intended to define the limits of the invention nor to confine the latter to any particular use. Various other changes and modifications may be made without departing from the spirit of the invention, and all of such changes are contemplated as may come within the scope of the claims.

What is claimed as the invention is:

1. Apparatus for controlling the flow of fluid fuel, comprising: A first flow-controlling member having condition responsive actuating means for actuating said flow-controlling member between a minimum stable flame flow-permitting position and an increased flow-permitting ignition position in response to changes in the condition; a second flow-controlling member movable to flow-preventing position in response to an extreme in said condition calling for a lesser flow than said minimum; and means for insuring safe ignition of the fuel including means for actuating said first flow-controlling member to said ignition position in response to movement of said second flow-controlling member to flow-preventing position.

2. Apparatus for controlling the flow of fluid fuel, comprising: A first flow-controlling member having condition responsive actuating means for actuating said flow-controlling member between a minimum stable flame flow-permitting position and an increased flow-permitting ignition position in response to changes in the condition; a second flow-controlling member movable to flow-preventing position in response to an extreme in said condition calling for a lesser flow than said minimum; and means for insuring safe ignition of the fuel, including means for actuating said first flow-controlling member to said ignition position in response to movement of said second flow-controlling member to flow-preventing position, and means for holding said first flow-controlling member in an increased flow-permitting position for a predetermined period after subsequent movement of the second flow-controlling member to flow-permitting position.

3. Apparatus for controlling the flow of fluid fuel comprising: A first flow-controlling member having condition responsive actuating means for actuating said flow-controlling member between a minimum stable flame flow-permitting position and an increased flow-permitting ignition position in response to normal fluctuations in the condition; a second flow-controlling member, condition responsive means for actuating said second flow-controlling member operable to effect movement of said member to a flow-preventing position in response to an extreme in the condition calling for lesser flow than said minimum; means responsive to movement of the second flow-controlling member to flow-preventing position for moving said first flow-controlling member to said ignition position; and means for holding said first flow-controlling member in an increased flow-permitting position for a predetermined period after movement of said second flow-controlling member to flow-permitting position.

4. Apparatus for controlling the flow of fluid fuel, comprising: A flow-controlling member biased toward a minimum flow-permitting position; condition responsive actuating mechanism for actuating said flow-controlling member between said minimum flow-permitting position and an increased flow-permitting ignition position against said bias in response to changes in the condition; an on-off valve; a diaphragm operatively connected to said flow-controlling member and having one side exposed to the fluid pressure of the fuel upstream from the on-off valve and having its other side exposed to the fluid pressure of the fuel downstream from the on-off valve, whereby upon closure of the latter valve the fluid pressure upstream

therefrom actuates said diaphragm and moves the flow-controlling member to said ignition position against said bias irrespective of the response of said condition responsive actuating mechanism to the ambient condition, the fluid pressure on the opposite sides of said diaphragm being equalized to release said flow-controlling member to the control of said condition responsive actuating mechanism when said on-off valve is opened; and time delay mechanism connected to said flow-controlling member and operable to retard the movement of the latter toward said minimum flow-permitting position under said bias when released by opening of said on-off valve, whereby said flow-controlling member is disposed in ignition position whenever said on-off valve is opened, and after a time delay, is returned to the control of said condition responsive actuating mechanism.

5. Apparatus for controlling the flow of fluid fuel, comprising: A flow-controlling member biased toward a minimum flow-permitting position; condition responsive actuating mechanism having a uni-directional separable force transmitting connection with said flow-controlling member for modulating the latter against said bias between said minimum flow-permitting position and an increased flow-permitting ignition position in response to changes in the condition; an on-off valve; and auxiliary actuating means directly connected to said flow-controlling member and responsive to closure of said on-off valve to overcall said condition responsive actuating mechanism and position said flow-controlling member in ignition position irrespective of the response of said condition responsive mechanism to the ambient condition, and to release said flow-controlling member to the control of said condition responsive mechanism in response to opening of said on-off valve; and uni-directional time delay mechanism directly connected to said flow-controlling member and operable to retard the movement of the latter toward said minimum flow-permitting position under said bias when released by opening said on-off valve, whereby said flow-controlling member is disposed in ignition position whenever said on-off valve is opened, and after a time delay, is returned to the control of said condition responsive actuating mechanism.

6. Apparatus for controlling the flow of fluid fuel, comprising: A flow-controlling member; a temperature responsive actuating mechanism for actuating said flow-controlling member between a minimum stable flame flow-permitting position and an increased flow-permitting ignition position in response to normal fluctuations in temperature; an on-off valve; apparatus including an electro-responsive operator for said on-off valve connected in circuit with a source of electrical energy; a circuit-controlling device in said operator circuit normally causing energization of said operator whereby the latter holds the on-off valve open, said circuit-controlling device being responsive to a predetermined high temperature to de-energize said operator to close said on-off valve, said circuit-controlling device being responsive to a subsequent drop in temperature below said predetermined high temperature to reenergize said operator and open said on-off valve; and auxiliary actuating means connected to said modulating flow-controlling member and operable to overcall said temperature responsive actuating mechanism and move said flow-controlling member to said ignition position in response to closure of said on-off valve irrespective of the response of the temperature responsive actuating mechanism to the ambient temperature.

7. Apparatus for controlling the flow of fluid fuel, comprising: A flow-controlling member biased toward a first position; an actuating mechanism for modulating said flow-controlling member between said first position and a second position against said bias and in response to normal fluctuations in the condition; an on-off valve; apparatus including an electro-responsive operator for said on-off valve connected in circuit with a source of electrical energy; a condition responsive circuit-control-

ling device in said operator circuit normally causing energization of said operator whereby the latter holds the on-off valve open, said circuit-controlling device being responsive to a predetermined extreme condition to de-energize said operator and close said on-off valve, said circuit-controlling device being responsive to a subsequent moderation of the condition to below said extreme condition to reenergize said operator and open said on-off valve; a diaphragm connected to said flow-controlling member and having one side exposed to the fluid pressure of the fuel upstream from the on-off valve and having its other side exposed to the fluid pressure on the downstream side of the on-off valve, whereby upon closure of the latter valve the fluid pressure upstream therefrom actuates said diaphragm and moves the flow-controlling member to said second position against said bias irrespective of the response of the condition responsive actuating mechanism to the ambient condition, the fluid pressure on the opposite sides of the said diaphragm being equalized to release the flow-controlling member to the control of said condition responsive actuating mechanism when said on-off valve is opened; and time delay mechanism connected to said flow-controlling member and operable to retard the movement of the latter toward said first position under said bias when released by opening of said on-off valve, whereby said flow-controlling member is disposed in said second position whenever said on-off valve is opened, and after a time delay, is returned to the control of the condition responsive actuating mechanism.

8. Apparatus for controlling the flow of fluid fuel, comprising: A flow-controlling member biased toward a minimum flow position; a temperature responsive actuating mechanism having a uni-directional separable force transmitting connection with said flow-controlling member for modulating said flow-controlling member against said bias between said minimum flow position and an increased flow-permitting ignition position in response to normal fluctuations in temperature; an on-off valve; apparatus including an electro-responsive operator for said on-off valve connected in circuit with a source of electrical energy; a thermostat in said operator circuit normally causing energization of said operator whereby the latter holds the on-off valve open, said thermostat being responsive to a predetermined high temperature to de-energize said operator and close said on-off valve, said thermostat also being responsive to a subsequent drop in temperature to below said predetermined high temperature to reenergize said operator and open said on-off valve; a diaphragm connected to said flow-controlling member for movement directly and continuously therewith, said diaphragm having one side exposed to the fluid pressure of the fuel upstream from the on-off valve and having its other side exposed to the fluid pressure on the downstream side of the on-off valve, whereby upon closure of the latter valve the fluid pressure upstream therefrom actuates said diaphragm and moves the flow-controlling member to said ignition position against said bias irrespective of the response of the temperature responsive actuating mechanism to the ambient temperature, the fluid pressure on the opposite sides of the said diaphragm being equalized to release the flow-controlling member to the control of said temperature responsive actuating mechanism when said on-off valve is opened; and uni-directional time delay mechanism connected to said flow-controlling member and operable to retard the movement of the latter toward said minimum flow position under said bias when released by opening of said on-off valve, whereby said flow-controlling member is disposed in said ignition position whenever said on-off valve is opened, and after a time delay, is returned to the control of the temperature responsive actuating mechanism.

9. Apparatus for controlling the flow of fluid, comprising first and second control members movable to first and second controlling positions, condition responsive

means for actuating said first control member from its first to its second controlling position in response to changes in the condition, and actuating means independent of said condition responsive actuating means and of which said second control member is independent for overcalling said condition responsive actuating means and actuating said first control member to its first controlling position in response to disposition of said second control member in its second controlling position irrespective of the response of said condition responsive actuating means to the ambient condition.

10. Apparatus for controlling the flow of fluid, comprising a first control member biased to a first controlling position and movable to a second controlling position, a second control member movable to first and second controlling positions, condition responsive means for actuating said first control member from its first to its second controlling position in response to changes in the condition, means for overcalling said condition responsive actuating means and actuating said first control member to its first controlling position against its bias in response to movement of said second control member to its second controlling position irrespective of the response of said condition responsive actuating means to the ambient condition, said overcalling means releasing said first control member for movement toward its first controlling position under its bias in response to movement of said second control member to its first controlling position, and time delay means operable to retard movement of said first control member from its second toward its first controlling position.

11. Apparatus for controlling the flow of fluid, comprising first and second control members movable to first and second controlling positions, condition responsive means for actuating said first control member from its first to its second controlling position in response to changes in the condition, an electroresponsive operator for said second control member connected in circuit with a source of electric energy, a circuit-controlling device in said operator circuit controlling the energization of said operator and thereby the position of said second control member, and actuating means independent of said condition responsive actuating means for overcalling the latter and moving said first control member to its first controlling position in response to disposition of said second control member in its second controlling position irrespective of the response of said condition responsive actuating means to the ambient condition.

12. Apparatus for controlling the flow of fluid, comprising first and second control members movable to first and second controlling positions, condition responsive means for actuating said first control member from its first to its second controlling position in response to normal fluctuations in the condition, an electroresponsive operator for said second control member connected in circuit with a source of electric energy, a condition responsive circuit controlling device in said operator circuit controlling the energization of said operator and thereby the position of said second control member, said circuit controlling device normally effecting disposition of said second control member in its first controlling position and being responsive to an extreme in the condition to effect movement of said control member to its second controlling position, and means independent of said condition responsive actuating means for overcalling the latter and actuating said first control member to its first controlling position in response to disposition of said second control member in its second controlling position irrespective of the response of said condition responsive actuating means to the ambient condition.

13. Apparatus for controlling the flow of fluid, comprising first and second control members movable to first and second controlling positions, condition responsive means for actuating said first control member from its first to its second controlling position in response to nor-

10 mal fluctuations in the condition, an electroresponsive operator for said second control member connected in circuit with a source of electric energy, and a circuit-controlling device in said operator circuit controlling the energization of said operator and thereby the position of said second control member, said circuit-controlling device normally effecting disposition of said second control member in its first controlling position and being positioned for actuation by said condition responsive actuating mechanism in response to an extreme condition to effect movement of said second control member to its second controlling position.

14. Apparatus for controlling the flow of fluid, comprising first and second control members movable to first and second controlling positions, condition responsive means for actuating said first control member from its first to its second controlling position in response to normal fluctuations in the condition, an electroresponsive operator for said second control member connected in circuit with a source of electric energy, a circuit-controlling device in said operator circuit controlling the energization of said operator and thereby the position of said second control member, said circuit-controlling device normally effecting disposition of said second control member in its first controlling position and being positioned for actuation by said condition responsive actuating mechanism in response to an extreme condition to effect movement of said second control member to its second controlling position, and means independent of said condition responsive actuating means for overcalling the latter and moving said first control member to its first controlling position in response to disposition of said second control member in its second controlling position irrespective of the response of said condition responsive actuating means to the ambient condition.

15. Apparatus for controlling the flow of fluid, comprising first and second control members each movable to controlling positions, condition responsive means for actuating said first control member between a first and second controlling position while holding said second control member in a first controlling position during normal fluctuations in the condition, said actuating means being responsive to an extreme in the condition to effect movement of said second control member to a second controlling position, and auxiliary actuating means for taking over control of said first control member and actuating the latter to its said first controlling position in response to movement of said second control member to its second controlling position, said auxiliary actuating means releasing said first control member for actuation by said condition responsive actuating means in response to movement of said second control member to its first controlling position, and time delay means operable to retard said release.

16. Apparatus for controlling the flow of fluid comprising first and second control members movable to first and second controlling positions, condition responsive first means for actuating said first control member from its first to its second controlling position in response to changes in the condition, second actuating means for said second control member, and third actuating means independent of said first actuating means for overcalling the latter and moving said first control member to its first controlling position responsive to movement of said second control member to its second controlling position irrespective of the response of said first actuating means to the ambient condition.

17. Apparatus for controlling the flow of fluid, comprising a first main fuel flow control member movable between a minimum flow-permitting and a maximum flow-permitting controlling positions, a second main fuel flow control member movable between flow-preventing and flow-permitting positions, condition responsive means for actuating said first control member from its minimum flow-permitting to its maximum flow-permitting control-

ling position in response to changes in the condition, and actuating means for overcalling said condition responsive actuating means and actuating said first control member to its maximum flow-permitting controlling position responsive to disposition of said second control member in its flow-preventing position irrespective of the response of said condition responsive actuating means to the ambient condition.

18. In a valve structure: means defining an elongated chamber having in communication with its opposite ends a main inlet and an outlet; a pair of valves arranged in series in said chamber so that fluid must pass through both of the valves from said main inlet to said outlet, one of the valves being adjacent the main-inlet end of the chamber and the other adjacent the outlet end; said chamber having intermediate said valves a restricted inlet through which fluid can pass when said one of the valves is closed and said other of the valves is open; means, including means movable gradually in response to variation of a controlling condition, for actuating the valves in such sequence, while said condition is varying in a given sense, that said one of the valves is closed before the other of the valves is closed, and means arranged so that opening movement is imparted to said one valve before opening movement is imparted to said other valve in response to variation of said condition in an opposite sense.

19. In a valve structure: means defining an elongated chamber having in communication with its opposite ends a main inlet and an outlet; a pair of valves arranged in series in said chamber so that fluid must pass through both of the valves from said main inlet to said outlet, one of the valves being adjacent the main-inlet end of the chamber and being of the type which comprises a closure positionable relative to a valve seat so as to vary and to obstruct flow, the other of the valves being adjacent the outlet end of the chamber and being of the on-off type; said chamber having intermediate said valves a restricted inlet through which fluid can pass when said one of the valves is closed and said other of the valves is open; means, including means movable gradually in response to variation of a controlling condition, for actuating the valves in such sequence, while said condition is varying in a given sense, that said one of the valves is closed before said other of the valves is closed, and means arranged so that opening movement is imparted to said one valve before opening movement is imparted to said other valve in response to variation of said condition in an opposite sense.

20. In a valve structure: a casing having an inlet and an outlet and a chamber therebetween; an inlet valve controlling flow from said inlet to said chamber and an outlet valve controlling flow from the chamber to said outlet; means, including means responsive to variation of a controlling condition, for actuating said valves arranged so that when said condition varies in a given sense the outlet valve is opened before movement of the inlet valve in opening direction, and the inlet valve is closed before the outlet valve is closed when the condition varies in the opposite sense; said chamber having a restricted opening leading to said inlet and by-passing the inlet valve so that when the outlet valve is open and the inlet valve is closed fluid can flow from said inlet to said outlet through the chamber and said restricted opening; means for supplying pressure fluid to said inlet; and a motor, operated in response to the change of fluid pressure in said chamber occurring upon closing and upon reopening of said outlet valve, for actuating said inlet valve independently of said actuating means and of the outlet valve, said motor being arranged to effect opening of the inlet valve upon closing of the outlet valve, and delayed closing of the inlet valve upon reopening of the outlet valve; said means for actuating said valves being arranged so that it is capable of actuating the inlet valve to open position against the force of said motor.

21. In a valve structure: a casing having an inlet and an outlet and a chamber therebetween; inlet valve means controlling flow from said inlet to said chamber and outlet valve means controlling flow from the chamber to said outlet; means, including means responsive to variation of a controlling condition, for actuating said valve means arranged so that when said condition varies in a given sense one of said valve means is opened before movement of the other of said valve means in opening direction, and said other valve means is closed before said one valve means is closed when the condition varies in the opposite sense; said casing having a restricted opening by-passing said other valve means so that when said one valve means is open and said other valve means is closed fluid can flow from said inlet to said outlet through the chamber and said restricted opening; means for supplying pressure fluid to said inlet; and a motor, operated in response to the change of fluid pressure in said chamber occurring upon closing and upon reopening of said one valve means, for actuating said other valve means independently of said actuating means and of said one valve means, said motor being arranged to effect opening of said other valve means upon closing of said one valve means, and delayed closing of said other valve means upon reopening of said one valve means; said means for actuating said valve means being arranged so that it is capable of actuating said other valve means to open position against the force of said motor.

22. Apparatus for controlling the flow of fluid comprising first and second control members movable to first and second controlling positions, first means for sequentially actuating said control members to their second controlling positions in response to a predetermined change in a given condition, and second actuating means independent of said condition responsive first actuating means for moving said first control member to its first controlling position responsive to movement of said second control member to its second controlling position irrespective of the response of said first actuating means to said given condition.

23. Apparatus for controlling the flow of fluid comprising first and second control members movable to first and second controlling positions, first means for sequentially actuating said first control member to its second controlling position and then said second control member to its second controlling position in response to a predetermined change in a given condition, and means for delaying return movement of said first control member toward its second position following movement of said second control member to its first position and second actuating means independent of said condition responsive first actuating means for moving said first control member to its first controlling position responsive to movement of said second control member to its second controlling position irrespective of the response of said first actuating means to said given condition.

24. Apparatus for controlling the flow of fluid comprising a modulator valve and an on-off valve each movable to closed and open positions, first actuating means for sequentially modulating said modulator valve to closed position and then moving said on-off valve to closed position in response to a predetermined change in temperature, and second actuating means independent of said first actuating means for moving said modulator valve to open position responsive to movement of said on-off valve to closed position irrespective of the response of said first actuating means to said temperature.

25. Apparatus for controlling the flow of fluid comprising a modulator valve and an on-off valve each movable to closed and open positions, first actuating means for sequentially modulating said modulator valve to closed position and then moving said on-off valve to closed position in response to a predetermined change in temperature, second actuating means independent of said first actuating means for moving said modulator valve to open

position responsive to movement of said on-off valve to closed position irrespective of the response of said first actuating means to said temperature, and means for delaying return movement of said modulator valve toward closed position following reopening of said on-off valve.

26. In a valve structure, means defining a chamber having an inlet and an outlet, a pair of valves arranged in series in said chamber so that fluid must pass through both of the valves from said inlet to said outlet, means defining a restricted bypass around one of said valves through which fluid can pass when said one valve is closed and the other valve is open, means, including means movable gradually in response to variation of a controlling condition, for actuating the valves in such sequence, while said condition is varying in a given sense, that said one valve is closed before said other valve is closed, and means arranged so that said one valve is opened before said other valve is opened.

27. In a valve structure: means defining a chamber having an inlet and an outlet, a pair of valves arranged in series in said chamber so that fluid must pass through both of the valves from said inlet to said outlet, one of said valves being of the type which comprises a closure positionable relative to a valve seat so as to vary and to obstruct flow, the other of the valves being of the on-off type, means defining a restricted bypass around said one valve through which fluid can pass when said one valve is closed and the other valve is open, means, including means movable gradually in response to variation of a controlling condition, for actuating the valves in such sequence, while said condition is varying in a given sense, that said one valve is closed before said other valve is closed, and means arranged so that said one valve is opened before said other valve is opened in response to variation of said condition in an opposite sense.

28. In a valve structure, means defining a chamber having an inlet and an outlet, a pair of valves arranged in series in said chamber so that fluid must pass through both of the valves from said inlet to said outlet, means defining a restricted bypass around one of said valves through which fluid can pass when said one valve is closed and the other valve is open, means, including means movable gradually in response to variation of a controlling condition, for actuating the valves in such sequence, while said condition is varying in a given sense, that said one valve is closed before said other valve is closed, and means arranged so that opening movement is imparted to said one valve before opening movement is imparted to said other valve.

29. In a valve structure: means defining a chamber having an inlet and an outlet, a pair of valves arranged in series in said chamber so that fluid must pass through both of the valves from said inlet to said outlet, one of said valves being of the type which comprises a closure positionable relative to a valve seat so as to vary and to obstruct flow, the other of the valves being of the on-off type, means defining a restricted bypass around said one valve through which fluid can pass when said one valve is closed and the other valve is open, means, including means movable gradually in response to variation of a controlling condition, for actuating the valves in such sequence, while said condition is varying in a given sense, that said one valve is closed before said other valve is closed, and means arranged so that opening movement is imparted to said one valve before opening movement is imparted to said other valve in response to variation of said condition in an opposite sense.

30. Apparatus for controlling the flow of fluid fuel, comprising: A control member movable to first and second controlling positions, condition responsive means comprising an electroresponsive actuator for actuating said control member between its first to its second controlling positions in response to changes in the condition, an on-off valve, and fluid pressure responsive actuating means operatively connected to said control member and

exposed to the pressure of the fuel upstream of said on-off valve whereby on closure of the said valve said fluid pressure responsive means responds to the increase in the fluid pressure upstream from said valve and actuates said control member toward its said second position, said pressure responsive actuating means also being responsive to a drop in said fluid pressure on opening of said valve to release said control member, said pressure responsive means including time delay means operable to retard said release.

31. Apparatus for controlling the flow of fluid comprising first and second control members movable to first and second controlling positions, first condition responsive electrically powered means for actuating said first control member between its first and its second controlling positions in response to changes in condition, and second actuating means responsive to movement of said said second control member to its first controlling position for overcalling said first actuating means and insuring disposition of said first control member in its second controlling position whenever said second control member is in its first controlling position.

32. Apparatus for controlling the flow of fluid, comprising first and second control members movable to first and second controlling positions, condition responsive means including an electroresponsive actuator for actuating said first control member between its first and its second controlling positions in response to changes in the condition, an electroresponsive operator for said second control member, and means for overcalling said condition responsive means and moving said first control member toward its second controlling position in response to movement of said second control member to its first controlling position.

33. Apparatus for controlling the flow of fluid comprising a first control member biased toward a first controlling position and movable toward a second controlling position, a second control member movable between first and second controlling positions, condition responsive electrically powered means for controlling the position of said first control member, said means comprising first actuating means operable when energized to position said first control member in said second controlling position and when deenergized to position said member in said first controlling position, second actuating means overcalling said first actuating means and moving said first control member toward its second controlling position in response to movement of said second control member to its first controlling position, said second actuating means releasing said first control member for movement toward its first controlling position by said first actuating means when deenergized in response to movement of said second control member to its second controlling position, and time delay means operable to retard movement of said first control member from its second toward its first controlling position.

34. Apparatus for controlling the flow of fluid, comprising first and second control members each movable to controlling positions, condition responsive means including an electroresponsive actuator for each of said control members for actuating said first control member between first and second controlling positions while retaining said second control member in a one controlling position in response to normal fluctuations in the condition, said means being responsive to an extreme in the condition to effect movement of said second control member to another controlling position, and auxiliary actuating means for taking over the control of said first control member and actuating the latter toward its second controlling position in response to movement of said second control member to its said other controlling position.

35. Apparatus for controlling the flow of fluid comprising first and second control members each movable to controlling positions, condition responsive means in-

cluding an electroresponsive actuator for each of said control members for actuating said first control member between a first and a second controlling position while retaining said second control member in a second controlling position in response to normal fluctuations in the condition, said means being responsive to an extreme in the condition to effect movement of said second control member to a first controlling position, auxiliary actuating means for taking over the control of said first control member and actuating the latter toward its first controlling position in response to movement of said second control member to its first controlling position, said auxiliary actuating means releasing said first control member in response to movement of said second control member to its second controlling position, and time delay means operable to retard said release.

36. Apparatus for controlling the flow of fluid, comprising first and second control members movable to first and second controlling positions, first electroresponsive actuating means for said first control member, a first condition responsive circuit controlling device in circuit with said electroresponsive actuating means and with a source of electric energy for controlling the energization of said actuating means and effecting movement of said first controlling member between first and second controlling positions in response to normal fluctuations in the condition, second electroresponsive actuating means for said second control member, a second condition responsive circuit controlling device connected in circuit with said second actuating means and a source of electric energy for controlling energization of said second actuating means and thereby the position of said second control member, said second circuit controlling device normally effecting disposition of said second control member in its second controlling position and being operable in response to an extreme in the condition to effect movement of said second control member to its first controlling position, and means for overcalling said first actuating means and moving said first control member toward its second controlling position in response to movement of the second control member to its first controlling position.

37. Apparatus for controlling the flow of fluid, comprising first and second control members movable to first and second controlling positions, first electroresponsive actuating means for said first control member, a first temperature responsive circuit controlling device in circuit with said electroresponsive actuating means and with a source of electric energy for controlling the energization of said actuating means and effecting movement of said first controlling member between said first and second controlling positions in response to normal temperature fluctuations, second electroresponsive actuating means for said second control member, a second temperature responsive circuit controlling device connected in circuit with said second actuating means and a source of electric energy for controlling energization of said second actuating means and thereby the position of said second control member, said second circuit controlling device normally effecting disposition of said second control member in its second controlling position and being operable in response to an extreme temperature to effect movement of said second control member to its first controlling position, and means for overcalling said first actuating means and insuring disposition of said first control member in its first controlling position in response to movement of the second control member to its first controlling position irrespective of the response of the first circuit controlling device to the ambient temperature.

38. Apparatus for controlling the flow of fluid, comprising first and second control members each movable to controlling positions, an electroresponsive actuator for each of said control members in circuit with a source of electric energy, condition responsive circuit controlling means having contacts in circuit with said electroresponsive

sive actuators for controlling the energization thereof and effecting actuation of said first control member between a first and a second controlling position while retaining said second control member in one controlling position during normal fluctuations in the condition, said circuit controlling means being responsive to an extreme in the condition to effect movement of said second control member to another controlling position, and auxiliary actuating means for actuating said first control member toward its second controlling position in response to movement of said second control member to its said other controlling position.

39. Apparatus for controlling the flow of fluid, comprising first and second control members each movable to controlling positions, an electroresponsive actuator for each of said control members in circuit with a source of electric energy, a two-stage thermostat having contacts in circuit with said electroresponsive actuators for controlling the energization thereof and effecting actuation of said first control member between a first and a second controlling position while retaining said second control member in one controlling position during normal temperature fluctuations, said thermostat being responsive to an extreme temperature to effect movement of said second control member to another controlling position, and auxiliary actuating means for actuating said first control member toward its second controlling position in response to movement of said second control member to said other controlling position.

40. Apparatus for controlling the flow of fluid, comprising first and second control members each movable to controlling positions, an electroresponsive actuator for each of said control members in circuit with a source of electric energy, a two-stage condition responsive circuit controlling device having contacts in circuit with said electroresponsive actuators for effecting actuation of said first control member between a first and a second controlling position while effecting retention of said second control member in one controlling position during normal fluctuations in the condition, said circuit controlling device being responsive to an extreme in the condition to effect movement of said second control member to another controlling position, auxiliary actuating means for actuating said first control member toward its second controlling position in response to movement of said second control member to its said other controlling position, said auxiliary actuating means releasing said first control member in response to movement of said second control member to its said one controlling position, and time delay means operable to retard said release.

41. Apparatus for controlling the flow of fluid, comprising first and second control members each movable to controlling positions, an electroresponsive actuator for each of said control members in circuit with a source of electric energy, a two-stage thermostat having contacts in circuit with said electroresponsive actuators for effecting actuation of said first control member between a first and a second controlling position while effecting retention of said second control member in one controlling position during normal temperature fluctuations, said thermostat being responsive to an extreme temperature to effect movement of said second control member to another controlling position, auxiliary actuating means for actuating said first control member toward its second controlling position in response to movement of said second control member to its said other controlling position, said auxiliary actuating means releasing said first control member in response to movement of said second control member to its one controlling position, and time delay means operable to retard said release.

42. Apparatus for controlling the flow of fluid fuel comprising, a high-low valve biased to low fuel flow permitting position and movable to high fuel flow permitting position, an on-off valve, first electroresponsive actuating means for controlling the positioning of said

high-low valve, said actuating means being operable when energized to position said high-low valve in high position and when deenergized to position said valve in low position, condition responsive circuit controlling means having contacts in circuit with a source of electric energy and with said electroresponsive actuating means for controlling the energization of the latter and effecting movement of said high-low valve between said high and low positions in response to changes in the condition, and second actuating means responsive to closure of said on-off valve for overcalling said first actuating means and insuring disposition of said high-low valve in said high position whenever said on-off valve is closed.

43. Apparatus for controlling the flow of fluid fuel comprising, a high-low valve having a low fuel flow-permitting position and movable to high fuel flow-permitting position, an on-off valve, first electroresponsive actuating means for controlling the positioning of said high-low valve, said actuating means being operable when energized to position said high-low valve in high position and when deenergized to position said valve in low position, condition responsive circuit controlling means having contacts in circuit with a source of electric energy and with said electroresponsive actuating means for controlling the energization of the latter and effecting movement of said high-low valve between said high and low positions in response to changes in the condition, and second actuating means responsive to closure of said on-off valve for overcalling said first actuating means and insuring disposition of said high-low valve in said high position whenever said on-off valve is closed, and means retarding movement of said high-low valve toward said low position by said first actuating means when deenergized on opening of said on-off valve after closure thereof.

44. Apparatus for controlling flow of fluid, comprising first control means having a condition responsive electroresponsive operator and a first control member movable thereby between first to second controlling positions in response to changes in condition, second control means including a second control member movable between first and second controlling positions, actuating means responsive to movement of said second control member to its first controlling position for overcalling said first control means and insuring disposition of said first control member in its second controlling position whenever said second control member is in its first controlling position.

45. In a valve structure, means defining a chamber having an inlet and an outlet, a high-low valve and an on-off valve arranged in series in said chamber, a restricted by-pass around said high-low valve permitting a low rate of fluid flow through said chamber from said inlet to said outlet when said high-low valve is closed and said on-off valve is open, electroresponsive operator means for said valves, condition responsive control means for said operator means causing the latter to actuate the valves in such sequence, while the condition is varying in a given sense, that said high-low valve is closed before the on-off valve is closed, and means operatively associated with said high-low valve for opening the latter before said on-off valve can be opened by said operator means in response to variation of said condition in an opposite sense.

46. In a valve structure, means defining a chamber having an inlet and an outlet, a high-low valve and an on-off valve arranged in series in said chamber, a restricted by-pass around said high-low valve permitting a low rate of fluid flow through said chamber from said inlet to said outlet when said high-low valve is closed and said on-off valve is open, electroresponsive operator means for said valves, condition responsive control means for said operator means causing the latter to actuate the valves in such sequence, while the condition is varying in a given sense, that said high-low valve is closed before the on-off valve is closed, means operatively associated with said high-low valve for opening the latter before said on-off valve can be opened by said operator means in response to a variation in said condition in an opposite sense, and means for retarding closure of said high-low valve following opening of said on-off valve.
